UNITED STATES PATENT OFFICE

HERMAN W. GOOSMANN, OF GRAND RAPIDS, MICHIGAN, ASSIGNOR TO SEM-PRAY JO-VE-NAY CO., OF GRAND RAPIDS, MICHIGAN, A CORPORATION OF MICHIGAN

CONTAINER

Application filed August 11, 1928. Serial No. 298,891.

This invention relates to the construction of a container or can particularly suited for semi-solid substances such as toilet creams and the like.

5 The main objects of this invention are to provide an improved container of the type which has a removable top and slidable bottom plate whereby the contents may be ejected by manually pushing upwardly on 10 said bottom plate; to provide a container particularly adapted to be filled, in an inverted position, with a semi-solid substance such as a toilet cream; and to provide a container which is relatively low priced to manufacture 15 and of rigid and durable construction.

An illustrative embodiment of this invention is shown in the accompanying drawings, in which:—

Fig. 1 is a view in vertical side elevation 20 of the improved container with the closure cap thereon.

Fig. 2 is a view of the same with the closure cap removed and the contents of the container partially ejected, the slidable bottom 25 plate being shown in dotted lines.

Fig. 3 is a sectional view taken on the line 3—3 of Fig. 4.

Fig. 4 is an enlarged vertical sectional view 30 of the container in an inverted position, the container being shown filled and with the closure cap and bottom plate in position.

In the construction shown in the drawings, the container comprises a sheet of metal having opposite edges thereof joined together by 35 a suitable lock seam 1 to form a casing 2, open at the top and bottom. In the specific embodiment shown, the casing 2 is oval in cross section, but it will be understood that the container may be formed in any suitable or 40 desirable shape.

The top marginal edge of the casing is folded outwardly and doubled back upon itself as shown at 3, to add rigidity to the container and at the same time provide a smooth 45 finished edge. A suitable cover or closure 4 is provided to fit over the top of the container and be retained thereon by friction.

The lower marginal edge of the casing is 50 folded inwardly and doubled back upon itself, as shown at 5. The doubled marginal

edge is beaded outwardly, as shown at 6, and the width of such bead is less than the width of the folded margin. That portion of the folded margin 5 that is not beaded protrudes inwardly from the inner wall of the casing to 55 form a seat 7 which is of less area than the cross sectional area of the casing.

The seat 7 is adapted to support a flexible or pliable bottom plate 8, preferably of cardboard or the like, which is slightly greater in 60 area than the cross sectional area of the casing so as to assume an inwardly bowed position, as shown in Figs. 2 and 4, when inserted in the casing through the open bottom end past 65 the seat 7.

This container is particularly adapted for being filled with a semi-solid or congealable material such as toilet creams. In filling the container, the closure 4 is placed on the top 70 end in snug frictional engagement with the flange 3. The container is then inverted and filled through the open bottom end, and then the pliable bottom plate 8 is forced into the bottom past the supporting seat 7. The plate is maintained in a slight bow due to it being 75 larger than the container and is retained from passing out through the bottom of the casing by engagement with the flange seat 7.

When it is desired to use the cream or other 80 material in the container, the closure 4 is removed and the bottom plate 8 is pressed upwardly by inserting a finger through the bottom of the casing. As the bottom plate is slidable in the casing, the plate and contents are slid upwardly, causing the material there- 85 in to project out the top of the container as shown at 9 in Fig. 2.

Although but one specific embodiment of 90 this invention has been herein shown and described, it will be understood that numerous details of the construction may be altered or omitted without departing from the spirit of this invention as defined by the following claim.

I claim:

A container comprising: a vertical tubular member having its lower end portion folded inwardly and upwardly to form a hollow seat; and a flexible upwardly convexing bottom member diametrically larger than the 100

hollow of the seat, and adapted to be inserted therethrough to supported position on the seat and in slidable relation with the tubular member above the seat, said bottom member being flexed to reduced diameter by the seat in passing through the hollow thereof.

In testimony whereof I have hereunto set my hand at Grand Rapids, Michigan, this 9th day of August, 1928.
